DRIVING MECHANISM FOR LAUNDRY
MACHINES

Walter K. Voss, Davenport, Iowa

Application September 28, 1934, Serial No. 745,902

6 Claims. (Cl. 74—75)

The invention relates generally to driving mechanism for laundry machines, and more particularly to washing machines of the household type which customarily embody a clothes wringing device.

An object of the invention is to provide mechanism of this nature which includes a novel means for disconnecting at will the action of the washing mechanism, such means being of a simple, economical construction embodying few parts in addition to those conventionally employed in such driving mechanisms, yet in operation being positive and efficient.

Another object of the invention is to provide a driving mechanism for the washer and wringer elements of a laundry machine which embodies novel means for connecting and disconnecting the driven eccentric by which the washer element is actuated from the gear member by which the wringer element is driven.

Other objects and advantages will become apparent in the following description and from the accompanying drawing in which

Figure 1 is a plan view of a driving mechanism embodying the features of the invention, the top of the housing being omitted and parts being in section for clarity.

Fig. 2 is a fragmentary generally vertical section through a laundry machine showing the arrangement of parts in the assembly of the driving mechanism.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the drawing, which show merely for illustrative purposes, a laundry machine in which the features of the invention are present, 10 designates a gear housing which is fixed in any suitable manner beneath the usual laundry tub 11. An oscillatory agitator 12 within the tub is adapted to be driven by means of a shaft 13 which extends upwardly through the tub bottom, suitable water tight bearings and fittings 14 being associated with the shaft and tub to prevent leakage. The shaft 13 extends downwardly from the tub through a sleeve 15 on the housing 10 and into said housing where it is engaged with a lower

bearing 16 and driving means to be presently described.

The housing extends horizontally beyond the side of the tub and a vertical shaft 17 is journaled as at 18, in the housing to extend upwardly through a sleeve 19 along the tub side. This shaft is conventionally used to drive a clothes wringing device (not shown).

A preferred form of driving mechanism for effecting operation of the shafts 13 and 17 comprises the following arrangement of parts. A suitable prime mover, herein shown as an electric motor 20, is mounted on the machine frame with its armature axis 21 extending vertically and its upper end supporting a pulley 22 or the like. An endless belt 23 engages pulley 22 and another pulley 24 on the outer end of a vertical stub shaft 25 which extends into and is suitably journaled on the housing. Within the housing the stub shaft has a pinion 26 fixed thereto near its lower end for driving engagement with a large gear 27 which is pinned as at 28 or otherwise rigidly secured to the wringer shaft 17. Through these connections the wringer shaft is constantly driven in one direction when the motor 20 is operating.

For driving the agitator shaft 13 with an oscillating movement, a disk 29 has a hub 30 located eccentrically thereon through which the wringer shaft 17 extends. The disk is therefore an eccentric element mounted loosely and rotatably upon the wringer shaft. The eccentric disk is normally positioned immediately adjacent to the gear 27 and the periphery of the disk is fashioned for engagement with an encircling or embracing strap 31. Formed integrally with the strap and extending radially therefrom is a pitman 32 for pivoted connection, as at 33, with a crank arm 34 secured near the lower end of the agitator shaft 13. When the eccentric disk is rotated, these connections are effective to translate such movement to an oscillatory movement of the agitator shaft.

A simple and efficient means is employed to drive the eccentric disk which involves a driving connection between said disk and the large gear 27 by which the wringer shaft is driven. Thus the gear 27 has, near its periphery, a series of elongated slots 35 disposed in end to end relation. The eccentric disk carries a pin 36 or the like which projects toward the gear and is adapted to enter any of the slots 35 to establish a driving connection between the disk and gear. The pin is relatively short, the length being such that shifting movement of the disk axially a distance just

insufficient to free the disk from the encircling strap 31 will effect disengagement of the pin and an engaged slot. The pin is herein shown as having screw-threaded engagement with the disk but it is evident that a cast projection or the like would serve.

The axial shifting movement of the disk may be suitably accomplished by such means as a shifting fork 37 engaging a groove 38 in the disk 10 hub 39 and having an actuating pin stud 39 secured thereto and extending from the housing in the direction of the wringer shaft. A handle 40 pivoted to the outer end of the stud has an eccentric cam action with the wall of the housing to 15 shift the stud and parts connected therewith and thereby effect movement of the eccentric disk along the wringer shaft. A spring 41 encircling the stud and bearing between the housing and the shifting fork urges the eccentric disk toward the gear 27 thereby normally to establish the driving 20 connection therebetween. A pin 42 on the wringer shaft or similar means may be employed to limit the extent of shifting movement of the disk away from the gear so that disengagement of the 25 disk and strap is prevented.

An antifriction means such as a washer 43 may be advantageously interposed between the eccentric disk and the gear to space these elements 30 slightly apart. This washer is of ample size to be engaged by one portion of the strap to eliminate an objectionable wiping or grinding action of the strap against the face of the gear.

It will be evident from the foregoing that a 35 novel structure and arrangement of parts in a disconnectable driving mechanism of this nature has been provided. Accurate fashioning of complementary clutch parts is eliminated since the slots may be easily cast in the gear while the pin may be cast on the disk or added thereto as a simple screw-threaded part. The assembly of the 40 structure is substantially the same as it would be without the disengageable feature and no extra parts are required other than the means by which the position of the disk is manually determined.

45 I claim as my invention:

1. A driving mechanism for laundry machines comprising, in combination, a wringer shaft having a driving gear affixed thereto, means for constantly driving said gear, an eccentric loosely mounted on said shaft in substantial face to face abutment with said gear, an agitator drive shaft, a crank and pitman mechanism operatively connecting said agitator drive shaft and said eccentric for effecting oscillation of said drive shaft 50 from the rotary movements of said eccentric, and including a strap encircling said eccentric, said gear having a series of slots of substantial length disposed in circular series near the periphery thereof, a pin carried by said eccentric for entry into any slot to establish a driving connection between said gear and eccentric, and manually controlled means for shifting said eccentric axially of said wringer shaft and within said strap a distance ample to move said pin clear of a slot engaged thereby and insufficient to disengage said eccentric from said strap.

2. In a driving mechanism of the character described, the combination of a constantly rotating shaft having a rotatable driving member fixed thereto, an oscillatable shaft, means connecting said driving member and said oscillatable shaft for translating rotary into oscillatory movement including an eccentric loosely mounted on said rotating shaft in face to face relation with said driving member and an encircling strap about 5 said eccentric, a pin and slot driving connection between said eccentric and driving member, and means for shifting said eccentric relative to said strap and toward and away from said driving member to establish and interrupt said driving connection.

3. In a driving mechanism of the character described, the combination of a constantly rotating shaft having a rotatable driving member therefor fixed thereto, an oscillatable shaft, connecting means for translating rotary movement 20 of said driving member into oscillatory movement of said oscillatable shaft including an eccentric loose on said rotating shaft and substantially in abutment with said driving member, a disengageable driving connection between said eccentric 25 and said driving member releasable by movement of said eccentric toward and away from said driving member, and manipulable means for effecting such movement.

4. In a driving mechanism of the character described, the combination of a driven rotatable member for driving a wringer shaft, an eccentric having a driving connection for oscillating an agitator shaft, means for supporting said eccentric for movement axially toward and away from 35 said rotatable member, and a driving connection between said eccentric and rotatable member respectively engageable and disengageable by such movement of the eccentric.

5. In a driving mechanism of the character described, the combination of a rotatable driving member for an operating shaft, an eccentric member for oscillating a second operating shaft, said members being located side by side for movement about the same center, means for shifting 45 one of said members relatively toward and away from the other member, and a driving connection between said members disengageable by relative separating movement of the movable member and engageable by relative approaching movement 50 thereof.

6. In a driving mechanism of the character described, the combination of a rotatable driving member and a driven eccentric member for effecting oscillatory movement of an operating 55 part and having an oscillatory movement transmitting element operatively associated therewith, said members being mounted for movement about substantially the same axis, a pin on said eccentric member extending in the direction of said driving member, said driving member having a pin receiving aperture therein, and means for manually shifting said eccentric member along its axis to engage or disengage said pin and slot while maintaining said operative association with 60 said element.
